UNITED STATES PATENT OFFICE.

A. STREVER, OF ALBANY, NEW YORK.

IMPROVEMENT IN HAMES-HOOK AND CLEVISSES.

Specification forming part of Letters Patent No. **86,188**, dated January 26, 1869.

To all whom it may concern:

Be it known that I, A. STREVER, of Albany, in the county of Albany, in the State of New York, have invented a new and useful Improvement in Hames-Hooks and Clevises; and I do hereby declare the following to be a full and complete description of my invention, reference being made to the accompanying drawings, and to the letters of reference marked thereon.

Figure 1 is a plan view. Fig. 2 is a sectional view.

Similar letters denote similar parts in each figure.

A represents a plate of malleable or wrought iron, being jointed or pivoted at the point C with the hook B, and at E with the hames, or to a cultivator or plow-beam, as the case may be, which makes it a universal joint, and does away with all strain on the hook, hames, or beam, in any direction the draft may be.

The plate A is made of the form of a circle on the end or side upon which the hook B turns, while the end of the hook is made just

long enough to move in close proximity to the arc, where it may be moved freely along to the notch D, where a ring of the harness may be slipped in, the hook moved over it, and the ring again withdrawn from the notch D, and the hook moved back, retaining the ring at the point F, without any liability to get out, as would be the case if the hook were used alone.

The advantage gained is that the universal joint does away with all side strain, while, the hook moving over the circular end of the plate and the notch, the ring may be admitted and held secure.

What I claim as my invention, and desire to secure by Letters Patent, is the following device, substantially as described, and for the purposes specified:

The hook B, pivoted to the plate A, having the circular end F, and the notch D.

A. STREVER.
